(57) **CLAIM**

The ornamental design for a battery-operated, LED infrared skin-treatment device as shown and described.

DESCRIPTION

FIG. 1 is an elevational front view of a battery-operated, LED infrared skin-treatment device in accordance with the present invention;

FIG. 2 is an elevational left-side view of the device of FIG. 1;

FIG. 3 is an elevational back-side view of the device of FIG. 1;

FIG. 4 is an elevational right-side view of the device of FIG. 1;

FIG. 5 is an elevational downward-looking view of the top of the device of FIG. 1;

FIG. 6 is an elevational upward-looking view of the bottom of the device of FIG. 1; and,

FIG. 7 is a perspective bottom-side view of the device of FIG. 1.

The broken lines showing buttons in the front center of the device and vents and a door on the rear of the device depict environment only and form no part of the claimed design.

1 Claim, 6 Drawing Sheets
